UNIVERSALLY ADJUSTABLE ANGLE BLOCK AND DRILL GUIDE ATTACHMENT FOR DRILL PRESS

Lloyd Bucha, 2916 U.S. 31 N., Niles, Mich.

Filed Jan. 18, 1965, Ser. No. 83,475

Term of patent 3½ years

(Cl. D54—13)

FIG. 1

FIG. 2

FIG. 3

FIG. 4

FIG. 5

FIGURE 1 is a perspective view of a universally adjustable angle block and drill guide attachment for drill press, embodying the present design and showing the angle block in one operating position;

FIGURE 2 is a side elevational view of the attachment shown in FIGURE 1 with the angle block in another operating position;

FIGURE 3 is a rear elevational view of the attachment;

FIGURE 4 is a front elevational view of the attachment, showing the angle block in another operating position; and

FIGURE 5 is a vertical cross sectional view, taken on line 5-5 of FIGURE 2.

I claim:

The ornamental design for a universally adjustable angle block and drill guide attachment for drill press, as shown and described.
